AMMUNITION LOADING DEVICE WITH
CHAIN CONVEYER FOR SMALL-ARMS

Giulio Sosso, Turin, Italy

Application June 19, 1934, Serial No. 731,246
In Italy June 26, 1933

4 Claims. (Cl. 42—6)

The automatic small-arms are generally loaded by means of a magazine, consisting of a narrow box open on one side, in which the cartridges are arranged one upon another. At each stroke 5 of the breech bolt, when the top cartridge is pushed into the barrel, the next cartridge is brought to the loading position by the action of a spring, the so-called elevator spring, arranged on the bottom of the magazine. When the magazine 10 contains a large number of cartridges, as it is generally the case in automatic fire-arms, it is of a considerable length, which however should not exceed a certain limit. The tension of the elevator spring is variable and when it is too 15 high (the magazine being completely loaded) it opposes a high resistance to the travel of the breech bolt and may stop it; while when the tension is too low (the magazine being nearly exhausted) it does not raise the cartridge quickly 20 enough and may stop when firing. The fire-arms provided with a feeding device in the form of a chain conveyer, such as certain machine guns, are free from this inconvenience and a great 25 number of cartridges may be placed on the feeding device.

This invention has for its object an automatic small-arm, the ammunition loading device of which comprises an endless band-conveyer for feeding the cartridges.

30 The main feature of the invention consists in the fact that pawl operated by the lock bolt and adapted to feed the endless conveyer cooperates directly with ratchets secured to the conveyer in a number corresponding to that of the cartridges 35 to be carried by the conveyer.

The annexed drawings show diagrammatically a loading device according to the invention applied to a pistol.

Figures 1, 2 and 3 show the ammunition loading device in three different positions.

Figure 4 shows diagrammatically a device for signalling when the conveyer is nearly emptied.

The pistol is of the usual construction wherein the feeding device is housed in the butt.

45 The pistol is of the recoiling barrel type. 21 is the frame, 22 the butt, the fixed part of which serves as a support for the feeding mechanism; the movable part serving as a cover for the feeding mechanism having been removed. 23 is a breech bolt provided as usual with an extractor and a striker 24. The butt houses the feeding device comprising an endless band and a box 25 with two drums 26 (Fig. 4) between which is stretched a band 27 carrying the cartridges 28 50 by means of resilient prongs 29. The feeding

device 25 is introduced through a lower opening in the butt, a cartridge is thus brought in the path of the bolt and held in place by a resilient pawl.

5 A crank lever 20 is hinged to the frame behind the conveyer and under the bolt; one arm 11 of said crank lever is caused to swing during the recoil by a tooth 31 and during the return stroke by a tooth 32. To the arm 12 of the crank lever is articulated a pawl 13, the hook of which engages ribs 14 on the conveyer 27, a rib being provided for each cartridge. The width of displacement of the lever 20 effected by the stop 31 is such as to move the pawl 13 to the required extent for advancing the conveyer by the distance 15 between two cartridges; the tray is returned idly under the action of the stop 32.

The steps of displacement of the pawl 13 are clearly illustrated in Figs. 1, 2 and 3. Fig. 3 shows that the pawl 13, though being free, maintains its angular position relatively to the arm 12 shown in Fig. 2 and changes said position by sliding on the face 15 of the frame owing to the friction in the joint between pawl and arm, which permits to dispense with the use of springs which 25 do not work satisfactorily chiefly owing to inertia when firing off volleys.

The bolt when recoiling causes the band to advance by one step carrying a cartridge to the place of the fired one; during its return stroke 30 it pushes said cartridge into the barrel. The passive resistances to overcome during the said operation are small being due first to the slight friction of the drums 26 of the conveyer and then to the light pressure of the prongs 9.

35 When on the contrary spring loading devices are used, the bolt on recoiling has to overcome the friction sliding on the cartridge pressed by the spring; on its return stroke the bolt in pushing the cartridge into the barrel has to overcome 40 the high friction produced by the spring between the cartridge and the edges of the magazine. The smaller effort to be effected by the bolt, according to this invention, permits the use of a stronger return spring or a more powerful closure, thus obtaining an increased range of the fire-arm.

45 The conveyer 25, as it has been said above, is introduced and extracted through a lower opening of the butt.

The spring controlled lever 16 pivoted to the frame engages by means of a tooth 17 a tooth 18 on the trigger 19, when the conveyer has been removed; when the conveyer is in position (Fig. 1) the lever disengages the trigger, the use of 55

which is thus prevented during the handling of the fire-arm (or the replacement of the conveyer), thus avoiding accidents due to the fact that the user of the fire-arm ignores the presence of a cartridge in the barrel.

5 The arm may be fired by single shots or volleys, working in this last case as a machine gun owing to the considerable capacity of the band conveyer, according as the trigger is pressed to a certain extent permitted by the resistance of a spring or pressed to the limit overcoming said resistance.

10 The arm of the feeler 30 (Fig. 4) controls the presence of the cartridges in the conveyer and 15 signals to the gunner slightly in advance that the loading tray is near to be empty.

15 The feeler 30 is in the form of a lever pivoted on a pin 33 through the housing of the conveyer, an arm of this lever abuts against a resilient plate on the frame 21 and the other arm 30 on 20 the band 27 through a longitudinal slot in the box 25 of the conveyer. As long as there is a cartridge under the arm 30, this latter does not prevent the trigger to be completely pressed down, so that volleys may be fired if desired. If on the contrary an empty space comes in front of the arm, this latter swings and limits by means of a suitable device the pressing down of the trigger.

25 The feeler signals when few cartridges are left 30 in the loading tray; these last cartridges may be fired only by single shots. The purpose of this mechanism is to prevent that the gunner when firing off volleys (in which case it is difficult to count and limit the shots) may remain fully 35 disarmed without previous notice and unable to get ready for the replacement of the loading tray.

The loading device above described may be used in connection with any automatic fire-arm with recoiling breech bolt.

40 What I claim is:

1. In combination with an automatic small-arm an ammunition loading device comprising, in combination with a breech bolt, an endless band conveyer for feeding the cartridges, ratchets secured to said band, one for each cartridge, a pawl adapted to engage said ratchets to push the endless band conveyer forward, a crank lever, on one arm of which is pivoted said pawl and a stop projection on the breech bolt, the other 45 50 arm of said lever projecting in the course of said projection thus pushing the band forward during recoil.

2. In combination with an automatic small-arm an ammunition loading device comprising, in combination with the frame of the firearm and a breech bolt slideable in said frame, an endless band conveyer for feeding the cartridges, 5 ratchets secured to said band, one for each cartridge, a pawl adapted to engage said ratchet, a crank lever on one arm of which said pawl is pivoted with a certain friction, so that the angular position of the pawl relatively to said arm 10 does not change as long as the pawl does not engage one of the ratchet teeth and two stop projections in spaced relationship on said breech bolt, the other arm of said lever projecting between said stop projections, thus pushing the 15 band forward during recoil of the breech bolt.

3. In combination with an automatic small-arm an ammunition loading device comprising, in combination with the frame of the firearm, a trigger and a breech bolt slideable in said frame, 20 a box, an endless band conveyer for feeding the cartridges mounted in said box, a housing in the frame for said box, a lever mechanism for locking said trigger as long as the box is not in place in said housing, ratchets secured to said band, 25 one for each cartridge, a pawl adapted to engage said ratchet to push the endless band conveyer forward, a crank lever, on one arm of which is pivoted said pawl and a stop projection on the breech bolt, the other arm of said lever project- 30 ing in the course of said projection thus pushing the band forward during recoil.

4. In combination with an automatic small-arm an ammunition loading device comprising, in combination with the frame of the fire-arm, 35 a trigger and a breech bolt slideable in said frame, a box, an endless band conveyer for feeding the cartridges mounted in said box, a housing in the frame for said box, a lever mechanism for locking said trigger as long as the box is not in place 40 in said housing, ratchets secured to said band, one for each cartridge, a pawl adapted to engage said ratchet, a crank lever on one arm of which said pawl is pivoted with a certain friction, so that the angular position of the pawl relatively to said arm does not change as long as the pawl 45 does not engage one of the ratchet teeth and a stop projection on the breech bolt, the other arm of said lever projecting in the course of said projection, thus pushing the band forward dur- 50 ing recoil of the breech bolt.

GUILIO SOSSO.
